FIG. 1 is a front view of a voltage regulator control in accordance with our design;

FIG. 2 is a perspective view of the voltage regulator control of FIG. 1, in accordance with our design;

FIG. 3 is a left side view of the voltage regulator control of FIG. 1, in accordance with our design;

FIG. 4 is a right side view of the voltage regulator control of FIG. 1, in accordance with our design;

FIG. 5 is a back view of the voltage regulator control of FIG. 1, in accordance with our design;

FIG. 6 is a top view of the voltage regulator control of FIG. 1, in accordance with our design; and,

FIG. 7 is a bottom view of the voltage regulator control of FIG. 1, in accordance with our design.

The broken line showing of voltage regulator control is for illustrative purposes only and forms no part of the claimed design.
